The ornamental design for a bowling lane return shroud and rail, as shown and described.

DESCRIPTION

FIG. 1 is a perspective view of a bowling lane return shroud and rail showing my new design;

FIG. 2 is a top plan view thereof;

FIG. 3 is a side view thereof; the opposite side being a mirror image thereof;

FIG. 4 is a front elevational view thereof; and,

FIG. 5 is a rear elevational view thereof.

FIG. 1

FIG. 4
